UNITED STATES PATENT OFFICE.

WILLIAM D. FOSS, OF CENTRALIA, WASHINGTON.

DESIGN FOR A SAW ATTACHMENT.

46,361.

Specification for Design.

Patented Sept. 8, 1914.

Application filed May 11, 1914. Serial No. 837,949. Term of patent 14 years.

To all whom it may concern:

Be it known that I, WILLIAM D. Foss, a citizen of the United States, and a resident of Centralia, in the county of Lewis and State of Washington, have invented a new, original, and ornamental Design for a Saw Attachment, of which the following is a specification, reference being had to the accompanying drawing, forming part thereof, in which—

Figure 1 is a perspective view of a saw

attachment showing my new design. Fig. 2 is a side elevation of a saw with the attachment in place thereon.

I claim:

The ornamental design for a saw attachment, as shown.

WILLIAM D. FOSS.
